DESIGN FOR A HANDLE BAR FOR A CYCLE

Herman L. Kraeft, Cleveland Heights, Ohio, assignor to The Murray-Ohio Manufacturing Company, Cleveland, Ohio, a corporation of Ohio

Application August 18, 1936, Serial No. 64,473

Term of patent 7 years

To whom it may concern:

Be it known that I, Herman L. Kraeft, a citizen of the United States, residing at Cleveland Heights, in the county of Cuyahoga and State of Ohio, have invented a new, original, and ornamental Design for a Handle Bar for a Cycle, of which the following is a specification, reference being had to the accompanying drawing, forming a part thereof.

In the drawing, Fig. 1 is a plan view of a handle bar for a cycle showing my new design; Fig. 2 is a perspective view of the same, Fig. 3 is a transverse sectional view, taken along the line 3—3 of Fig. 1.

I claim:

The ornamental design for a handle bar for a cycle, substantially as shown.

HERMAN L. KRAEFT.
